WITNESS:

UNITED STATES PATENT OFFICE.

JAMES E. ROGERS, OF CLEVELAND, OHIO, ASSIGNOR OF ONE-HALF TO GEORGE E. BLACK, OF CLEVELAND, OHIO.

TOY.

1,385,275.

Specification of Letters Patent. Patented July 19, 1921.

Application filed August 27, 1920. Serial No. 406,277.

To all whom it may concern:

Be it known that I, JAMES E. ROGERS, a citizen of the United States, residing at Cleveland, in the county of Cuyahoga and 5 State of Ohio, have invented new and useful Improvements in Toys, of which the following is a specification.

The invention relates to toys and more particularly to that class of toys simulating 10 animals or figures and arranged to have moving parts, whereby manual operation of one of the moving parts brings about automatic movement of another to bring about a comical or amusing operation of the toy 15 as to the moving parts.

The invention comprehends among other features the provision of a toy which may be made to simulate an animal and in which a rear portion such as the hind legs are 20 mounted to move upon the body and are arranged to have connection with a front portion such as the head of the body so that movement of the rear portion into set position causes the head to be set in a certain 25 position and has a trigger or release member whereby when the head is actuated a suitable spring will bring about operation of the rear portion or hind legs, simulating a kicking action of an animal such as a horse, 30 donkey or the like.

Still further the invention comprehends a mechanical toy which because of the few and simple arrangements of the parts can be cheaply manufactured and cannot readily 35 get out of order.

In the further disclosure of the invention, reference is to be had to the accompanying drawings, constituting a part of this specification, in which similar characters of reference denote corresponding parts in all the 40 views, and in which,—

Figure 1— is a side elevation of the toy showing the same set for operation, parts of the side of the body being broken away 45 to disclose the underlying structure.

Fig. 2— is a similar view showing the position of the moving parts after the device has been operated; and

Fig. 3— is a vertical sectional view taken 50 substantially on the line 3—3 in Fig. 1.

Referring more particularly to the views, the numeral 10 indicates a base and the numeral 11 a body which may be formed to simulate an animal such as a horse, the body

including the main portion 12, providing 55 an interior chamber or compartment 13 and fore-legs 14 constituting the uprights for the support of the body and having rigid connection with the base at its forward end. The moving parts for the completion of 60 the body consists of a head or front portion 15 pivoted as at 16 and extending outwardly through a slot 17 and communicating with the interior thereof, with hind legs or a rear portion 18 connected by a cross spindle or 65 shaft 19 mounted to swing upon the rear portion of the body 11. The lower and inner end of the front portion 15 carries a rearwardly extending trigger member 20, arranged longitudinally of the body 11 and 70 including a tail portion 21 terminating in an upwardly curved guide 22 and a trigger 23, the latter being formed by notching the member 20 to provide a projection which forms the trigger. The cross spindle 19 75 carries a U-shaped depending stirrup 24 through which the tail portion 21 extends and a somewhat similar stirrup or member 25 is carried by the spindle 19 and extends upwardly for connection thereof to one end 80 of an elastic band or spring member 26, the other end of which is secured by a staple or securing member 27 to the front portion 15.

When the device is in the position shown 85 in Fig. 2, and it is desired to set the same, the hind legs or rear portion 18 is swung forwardly thus bringing the elastic band 26 into tension and causing the stirrup 24 to be brought into a position adjacent the trigger 90 23. When this movement occurs, the resulting tension of the elastic band also causes the head or front portion 15 to swing upwardly thereby swinging the trigger downwardly so that it will engage and catch with the stirrup 24. The device is now set with the rear portion 18 held by the trigger in engagement with the stirrup. When the head or front portion 15 is now swung downwardly, an upward movement will be imparted to the 100 trigger 23 releasing the same from engagement with the stirrup 24 and the consequent pull of the elastic band 26 will cause the rear portion or hind legs 18 to swing outwardly, simulating a kicking action.

It will be apparent that the elastic band or spring member serves a two-fold function in that it brings the desired pull or tension

on to the rear portion or hind legs when they are set so that they will subsequently swing forward when they are released and also by reason of this pull upon the head or front portion, brings the trigger into position to engage with the stirrup as mentioned.

As stated heretofore it will be understood that I do not restrict myself to the particular shape and design of the toy disclosed in 10 the drawings; that various forms and simulations may be brought about without departing from the mechanical construction and operation and that the few and simple parts involved in the construction provides for a 15 toy that can be very cheaply manufactured and cannot readily get out of order.

Having described my invention, I claim—

1. A toy comprising a body, an actuating member mounted to swing on the body, a 20 spindle journaled on the body, a movable member carried by the spindle, a stirrup projecting from the spindle, an extension actuating member, a trigger formed on the extension to engage with the stirrup, a guide 25 on the extension for guiding the stirrup relative to the trigger and a tension member con-

necting with the actuating member and said spindle.

2. A toy comprising a body having a hollow interior and a communicating slot, a 30 head mounted to swing on the body with a portion of the head disposed in the interior thereof and another portion projecting through the slot, a rearwardly extending extension on the head and extending through 35 the interior of the body to the rear thereof, a movable member mounted to swing on the body, a projection connecting with said movable member and stationary therewith and said projection being engaged by said trigger, a second projection connecting with the movable member and stationary therewith and spring-like means disposed in the interior of the body and connecting with the 40 head to one side of the pivotal connection 45 thereof with the body and also connecting with said second projection to one side of the point of swinging connection of the movable member with the body.

In testimony whereof I affix my signature. 50

JAMES E. ROGERS.
